UNITED STATES PATENT OFFICE.

FREDERICK A. JAMES, OF CLEVELAND, OHIO.

ROTARY CLEANING DEVICE.

1,236,307.

Specification of Letters Patent. Patented Aug. 7, 1917.

Application filed October 17, 1916. Serial No. 126,200.

To all whom it may concern:

Be it known that I, FREDERICK A. JAMES, a citizen of the United States, residing at Cleveland, in the county of Cuyahoga, and 5 State of Ohio, have invented new and useful Improvements in Rotary Cleaning Devices, of which the following is a specification.

This invention relates to a tool primarily designed for ship clearing, boiler scraping 10 and like analogous uses, and embodies a peculiar formation of a frame upon which a rotary tool and motor for operating the same can be conveniently disposed in working relation.

15 The nature and advantages of the invention will be readily apparent when the following description is read in connection with the accompanying drawing, the invention residing in the specific construction, combination and arrangement of parts as claimed.

In the drawing forming part of this specification like numerals of reference indicate similar parts in the several views and wherein:

25 Figure 1 is an elevation of the tool constructed in accordance with my invention.

Fig. 2 is a top plan view of the frame with the motor removed.

A tool constructed in accordance with my 30 invention embodies a frame indicated generally at A and having a relatively narrow end portion constituting a support for the motor B, and a relatively broad end portion upon which the rotary tool C is journaled.

35 The frame may be constructed from any suitable material, preferably from strap iron and including spaced members 10 and 11 respectively. The members are twisted at appropriate points in their length as at 12, 40 whereby the corresponding portions at one side of the twisted portion are disposed horizontally in close proximity to each other to afford a satisfactory base or support for the motor B. The extremities of the horizontally 45 disposed portions 13 are connected by means of a suitable handle 14. The members 10 and 11 in advance of the twisted portion 12 diverge outwardly as at 15 and are then extended in parallelism, and constitute bearings for the shaft 16 of a rotary tool. The

tool C may be in the nature of a brush, or a scraper constructed in the manner illustrated and is admirably designed for cleaning ships, or scraping boilers. When constructed in the manner illustrated the tool 50 comprises a cylindrical member provided with longitudinally arranged slots in which is secured tangentially disposed combined striking and scraping blades. These blades are beveled and due to their arrangement 55 will effectively scrape rust or other foreign matter from surfaces which have been previously loosened by the striking or contacting of the preceding blades. The shaft 17 of the motor B, as well as the shaft 16 of the 60 rotary tool C is provided with a grooved wheel 18 over which is trained a belt 19 whereby the tool C is rotated when the motor B is in operation. The motor B may be 65 of any suitable character, preferably an electric motor, and embodies among other features a base 20 provided with suitable openings and adapted to register with openings 21 of the horizontal portions 13 of the frame, for the reception of suitable fastening elements 22 by means of which the motor 70 is secured rigidly to the frame. A series of openings 21 is provided whereby the motor B can be moved toward and away 75 from the tool C, and when moved away from the latter effects an adjustment for the tightening of the belt 19. A handle 23 projects laterally from one side of the frame at right angles to the handle 14 whereby the tool in 80 its entirety can be conveniently handled 85 when its use is desired.

By the arrangement of the handles 14 and 23 the contact of the tool C with the surface to be cleaned may be conveniently regulated, either one of the handles acting as a fulcrum, so that the impact of the blades of 85 the tool may be greater or less as desired, the arrangement of the handles permitting 90 this to be regulated to a nicety.

What is claimed is:

1. A device of the class described comprising a frame, a combined hammering and scraping tool rotatably mounted therein and transversely thereon, a motor mounted upon 95 said frame for operating said tool and han- 100

dles secured to said frame, whereby, the force of contact of the tool with the work may be regulated.

2. The combination with a motor driven cleaning device including a frame having a motor thereon and handles therefor, of a rotary member, tangentially arranged com-

bined hammering and scraping blades carried by said member and mounted transversely on said frame and driving means connecting the motor with said rotary member. 10

In testimony whereof I affix my signature.

FREDERICK A. JAMES.
